UNITED STATES PATENT OFFICE.

CHARLES F. STODDARD, OF BOSTON, MASSACHUSETTS, ASSIGNOR TO
AMERICAN PNEUMATIC SERVICE COMPANY, OF DOVER, DELAWARE,
A CORPORATION OF DELAWARE.

PNEUMATIC-DESPATCH APPARATUS.

SPECIFICATION forming part of Letters Patent No. 742,516, dated October 27, 1903.

Application filed May 28, 1903. Serial No. 159,064. (No model.)

To all whom it may concern:

Be it known that I, CHARLES F. STODDARD, of Boston, in the county of Suffolk and State of Massachusetts, have invented certain new and useful Improvements in Pneumatic-Despatch Apparatus, of which the following is a specification.

My invention relates to new and useful improvements in terminals for pneumatic-despatch apparatus, and especially to such apparatus wherein large carriers are used for the transmission of mail-matter and merchandise.

The object of my invention is to produce a terminal simple in construction and efficient in operation.

My invention consists of certain novel features hereinafter described, and particularly pointed out in the claims.

In the accompanying drawings, which illustrate a construction embodying my invention, Figure 1 is a longitudinal section through the terminal with the parts in position to receive a carrier. Fig. 2 is a similar view through the terminal after a carrier has been received and is being discharged.

Like letters of reference refer to like parts throughout the views.

The main transmission-tube A is located in alignment with the compression-chamber A² of the terminal and beyond the slotted casing A', through which the pressure passes into the return-tube A³. Located on the upper side of the compression-chamber A² is the cylinder D⁴, connected with the compression-chamber A² by the pipe C⁶, and located within said cylinder is the piston D², connected by the rod D⁸ with the piston-valve D', which in turn is connected by the rod D⁵ to the rod D⁷ by the beveled joint D⁶. The rod D⁷ is pivotally connected to the finger D⁸ at E, and this finger D⁸ swings on the bracket E', to which it is pivotally connected at E', and this finger D⁸ normally extends into the path of travel 45 of the discharging carrier, as shown in dotted lines, Fig. 2. The air supplied for operating the inner and outer gates B and B² in the terminal enters through the pipe C into the valve-casing D and is conveyed into the top

of the inner and outer cylinders B⁶ and B⁵ by 50 the pipes C' C² and operates the pistons B⁴ B⁷, to which are respectively connected the gates B and B² by the piston-rods B⁵ and B'. The carrier coming into the compression-chamber A² is brought to a stop by the compression of 55 the air in front of it as the gate D² is closed. This pressure passes by the pipe C⁶ into the cylinder D⁴ and forces the piston D² to the left of the cylinder D⁴, as shown in Fig. 2. This movement of the piston D² moves the 60 piston-valve D' from the position shown in Fig. 1 to that shown in Fig. 2 and also brings the finger down into the position shown in fulllines, Fig. 2. The air-supply entering the valve-casing D through the pipe C then passes 65 through the pipe C, then passes through the pipe C' to the upper side of the piston B⁴ in the cylinder B⁶, and closes the gate B. As the piston B⁴ reaches the lower end of the cylinder B⁶ it passes the port P, which admits the pressure to the under side of the piston B⁷ in the cylinder B⁵ through the pipe C⁴. This pressure raises the piston B⁷ to the upper end of the cylinder B⁵, causing the raising of the gate B², which is connected to the 75 piston B⁷ by the rod B'. A portion of the pressure from the line A passes through the port P² in the gate B into the chamber A² back of the carrier and forces the carrier out of the chamber A² onto the table A⁴. In this position of 80 the parts, Fig. 2, the finger B⁸ is in the path of the carrier, which strikes it as it comes onto the table A⁴ after it has passed the outer gate B². The finger D⁸ is moved from the position shown in full lines Fig. 2 to that shown in 85 full lines Fig. 1 by the carrier which moves the piston-valve from the position shown in Fig. 2 to that shown in Fig. 1, thereby opening the pipe C' to the atmosphere to allow the pressure in it and the cylinder B⁶ to exhaust 90 to the atmosphere. The pressure from the pipe C then passes through the pipe C² into the cylinder B⁵ above the piston B⁷ and forces it down into the position shown in Fig. 1. As the piston B⁷ reaches the lower end of the 95 cylinder B⁵ it passes the port P' and allows the pressure on the upper side of the piston B⁷ to pass through the pipe C³ to the under

side of the piston B⁴ in the cylinder B⁶, thereby raising the piston B⁴ to the position shown in Fig. 1, which places the apparatus in position to receive another carrier. The pipe 5 C⁵, connected to the cylinder D⁴, is for the purpose of balancing the piston D² when the machine is not in operation. A⁹ is a suitable buffer to stop the carrier when it reaches the end of the table A⁴.

15 I do not limit myself to the arrangement and construction shown, as the same may be varied without departing from the spirit of my invention.

Having thus described the nature of my invention and set forth a construction embodying the same, what I claim as new, and desire to secure by Letters Patent of the United States, is—

20 1. In an apparatus of the character described, a transmission-tube, a terminal communicating with said tube, an inner and an outer gate closing the same, an inner and an outer cylinder each having a piston connected to said gates, a source of air-pressure for operating said pistons, communication between said cylinders and said source of air-pressure, 25 a valve for opening and closing said communication to each cylinder alternately, mechanism operated by the pressure in the tube for normally closing communication between said source of compressed air and the inner cylinder, mechanism operated by air compressed by the carrier for operating said valve to open communication between said source of compressed air and the inner cylinder to close the inner gate and to close communication between said source of compressed air and the outer cylinder to open the outer gate, and a connection between the inner cylinder and the outer cylinder for leading the pressure from the outer cylinder to the inner cylinder to open the inner gate after the outer gate is closed.

25 2. In an apparatus of the character described, a transmission-tube, a terminal communicating with said tube, an inner and an outer gate closing the same, an inner and an outer cylinder each having a piston connected to said gates, a source of air-pressure for operating said pistons, communication between said cylinders and said source of air-pressure, 30 a valve for opening and closing said communication to each cylinder alternately, mechanism operated by the pressure in the tube for normally closing communication between said source of compressed air and the inner cylinder, mechanism operated by air compressed by the carrier for operating said valve to open communication between said source of compressed air and the inner cylinder to close the inner gate and to close communication between said source of compressed air and the outer cylinder to open the outer gate, and a connection between the inner cylinder and the outer cylinder for leading the pressure from the outer cylinder to the inner cylinder to open the inner gate after the outer gate is closed.

35 3. In an apparatus of the character described, a transmission-tube, a terminal communicating with said tube, an inner and an outer gate closing the same, an inner and an outer cylinder each having a piston connected to said gates, a source of air-pressure for op-

erating said pistons, communication between said cylinders and said source of air-pressure, a valve for opening and closing said communication to each cylinder alternately, mechanism operated by the pressure in the tube for normally closing communication between said source of compressed air and the inner cylinder, and connections between said cylinders for leading the pressure therefrom alternately to one another.

4. In an apparatus of the character described, a transmission-tube, a terminal communicating with said tube, an inner and an outer gate closing the same, an inner and an outer cylinder each having a piston connected to said gates, a source of air-pressure for operating said pistons, communication between said cylinders and said source of air-pressure, 80 a valve for opening and closing said communication to each cylinder alternately, mechanism operated by the pressure in the tube for normally closing communication between said source of compressed air and the inner cylinder, mechanism operated by air compressed by the carrier for operating said valve to open communication between said source of compressed air and the inner cylinder to close the inner gate and to close communication between said source of compressed air and the outer cylinder to open the outer gate, and a connection between the inner cylinder and the outer cylinder for leading the pressure from the inner cylinder to the outer cylinder after the inner gate is closed to open the outer gate.

5. In an apparatus of the character described, a transmission-tube, a terminal communicating with said tube, an inner and an outer gate closing the same, an inner and an outer cylinder each having a piston connected to said gates, a source of air-pressure for operating said pistons, communication between said cylinders and said source of air-pressure, 90 a valve for opening and closing said communication to each cylinder alternately, mechanism operated by the pressure in the tube for normally closing communication between said source of compressed air and the inner cylinder, mechanism operated by air compressed by the carrier for operating said valve to open communication between said source of compressed air and the inner cylinder to close the inner gate and to close communication between said source of compressed air and the outer cylinder to open the outer gate, and a connection between the inner cylinder and the outer cylinder for leading the pressure from the inner cylinder to the outer cylinder 95 after the inner gate is closed to open the outer gate, and a connection between the inner cylinder and the outer cylinder for leading the pressure from the outer cylinder to the inner cylinder 100 after the outer gate is closed to open the inner gate.

6. In an apparatus of the character described, a transmission-tube, a terminal communicating with said tube, an inner and an

- outer gate closing the same, an inner and an outer cylinder each having a piston connected to said gates, a source of air-pressure for operating said pistons, communication between said cylinders and said source of air-pressure, a valve for opening and closing said communication to each cylinder alternately, mechanism operated by the pressure in the tube for normally closing communication between said source of compressed air and the inner cylinder, mechanism operated by air compressed by the carrier for operating said valve to open communication between said source of compressed air and the inner cylinder to close the inner gate and to close communication between said source of compressed air and the outer cylinder to open the outer gate, and a connection between the inner cylinder and the outer cylinder for leading the pressure from the inner cylinder to the outer cylinder after the inner gate is closed to open the outer gate, the said inner gate having an opening through which pressure passes and drives the carrier from the terminal.
7. In an apparatus of the character described, a transmission-tube, a terminal communicating with said tube, an inner and an outer gate closing the same, an inner and an outer cylinder each having a piston connected to said gates, a source of air-pressure for operating said pistons, communication between said cylinders and said source of air-pressure, a valve for opening and closing said communication to each cylinder alternately, mechanism operated by the pressure in the tube for normally closing communication between said source of compressed air and the inner cylinder, mechanism operated by air compressed by the carrier for operating said valve to open communication between said source of compressed air and the inner cylinder to close the inner gate and to close communication between said source of compressed air and the outer cylinder, and connections between the inner and the outer cylinders for leading the pressure alternately from one cylinder to another for alternately opening said gates.
8. In an apparatus of the character described, a transmission-tube, a terminal communicating with said tube, an inner gate and an outer gate closing the terminal, an inner and an outer cylinder each having a piston connected to said gates, a source of air-pressure for operating the piston to close the gates, communication between said cylinders and said source of air-pressure, a valve for opening and closing said communication to each cylinder alternately, mechanism operated by the pressure in the tube for normally closing communication between said source of compressed air and the inner cylinder, mechanism operated by air compressed by the carrier for operating said valve to open communication between said source of compressed air and the inner cylinder to close the inner gate and to close communication between said source of compressed air and the outer cylinder, and connections between the inner and the outer cylinders for leading the pressure alternately from one cylinder to another for alternately opening said gates.

In testimony whereof I have signed my name to this specification, in the presence of two subscribing witnesses, this 21st day of May, A. D. 1903.

CHARLES F. STODDARD.
